US00D492248S1

(12) **United States Design Patent** (10) Patent No.: **US D492,248 S**
Gregory et al. (45) Date of Patent: **** Jun. 29, 2004**

(54) **BATTERY PACK FOR WIRELESS ECG MONITORING SYSTEM**

(75) Inventors: **William W. Gregory**, Fort Lauderdale, FL (US); **David Paul Chastain**, Acton, MA (US); **John David Gundlach**, Acton, MA (US); **Scott Chapps**, New York, NY (US); **Richard O'Brien**, Waltham, MA (US); **Robert Brady**, Sarasota, FL (US); **Joel Chartier**, Bradenton, FL (US)

(73) Assignee: **GMP Wireless Medicine, Inc.**, Fort Lauderdale, FL (US)

(**) Term: **14 Years**

(21) Appl. No.: **29/188,789**

(22) Filed: **Aug. 22, 2003**

(51) LOC (7) Cl. **13-02**

(52) U.S. Cl. **D13/103**

(58) Field of Search **D13/107, 108; 320/107-116**

(57) **CLAIM**

The ornamental design for a battery pack for wireless ECG monitoring system, as shown and described.

DESCRIPTION

FIG. 1 is a perspective view showing the new design;

FIG. 2 is a rear plan view thereof;

FIG. 3 is a front plan view thereof;

FIG. 4 is a left side elevational view thereof;

FIG. 5 is a right side elevational view thereof;

FIG. 6 is a top view thereof; and,

FIG. 7 is a bottom view thereof.
